UNITED STATES PATENT OFFICE.

HEINRICH CHRISTIANSEN, OF PINNEBERG, GERMANY.

MACHINE FOR USE IN TRANSMITTING ENERGY BY MEANS OF ALTERNATELY-MOVING AIR-COLUMNS.

1,244,955.

Specification of Letters Patent. Patented Oct. 30, 1917.

Application filed October 26, 1916, Serial No. 127,831. Renewed September 17, 1917. Serial No. 191,903.

To all whom it may concern:

Be it known that I, HEINRICH CHRISTIANSEN, a citizen of the German Empire, resident at Pinneberg, in the Kingdom of Prussia, German Empire, have invented new and useful Improvements Relating to Machines for Use in Transmitting Energy by Means of Alternately-Moving Air-Columns, of which the following is a specification.

10 This invention relates to machines adapted to produce alternate to and fro movements of air-columns, which air-columns can be employed in turn for the operation of percussion tools, the alternate to and fro movements of the air-columns causing the reciprocation of a piston-hammer which, in its movement in one direction, strikes the rear end of the tool proper, such for example as a rock tool or chisel. The air columns are 15 moved backward and forward at a rate dependent upon the number of revolutions per minute of the machine, and they cause a corresponding number of impulses to be given by the hammer-piston of the percussion tool. In view of the fact that the 20 number of impulses per minute which must be imparted to the tool for many kinds of work is very high, for example 1,000, 2,000 or even more strokes per minute the machine is subjected to very heavy shocks by the reciprocating masses, and its parts are 25 subjected to heavy stresses resulting in rapid wear while largely increasing the difficulty of erecting the transportable machine. Machines of this kind have frequently to be 30 erected on high structures, for example in connection with bridge construction, shipbuilding and the like, and they must be safely mounted in position on such structures without any special means of attachment.

In the machine as constructed according to the present invention, the wearing away of the moving parts is slight owing to the 45 particular arrangement adopted. The new machine is very compact and is easy to erect. Shocks or vibrations in the machine, even at the highest speeds of working, are reduced to such an extent that they are 50 quite harmless and are almost imperceptible. The reciprocating pistons which serve for imparting the alternate to and fro movements to the columns of air are driven from the inside thereof. The resistance to ac-

celeration and at other moments to de-celeration of the moving parts is balanced by the known expedient of duplication of the moving parts which move in opposite directions in pairs, and the particular means employed for actuating the pistons assists in attaining the same object; in this way the creation of unbalanced force-couples is substantially obviated.

In the accompanying drawings Figures 1 to 3 show one example of construction according to this invention, and Figs. 4 to 6 show a second example of construction.

Fig. 1 shows a longitudinal section of the machine.

Fig. 2 shows a cross section on the line A—B of Fig. 1.

Fig. 3 shows a longitudinal section of a piston on the line C—D of Fig. 2.

Fig. 4 shows a longitudinal section of a modified construction of the machine.

Fig. 5 shows a section of a piston at right angles to Fig. 4, and

Fig. 6 shows a cross section of a piston.

In the example of construction shown in Figs. 1 to 3, *a* is a cylinder to which is secured a casing *b* for the reception of the driving wheels *r'* and *r''*. The cylinder *a* is closed at its two ends by cover plates *c'* and *c''*. In the cylinder *a* are mounted two pistons *d'* and *d''* adapted to be moved toward and away from one another. Each of the pistons *d'* and *d''* is composed of two parts which are connected together by two bolts. The bolts *e'*, *e''* serving to connect together the two parts of the piston *d'* are shown in Figs. 2 and 3. The two parts of the piston *d''* are connected together in a similar manner. The two halves of the piston *d'*, and similarly the two halves of the piston *d''* form in each case a straight guide *f'* or *f''* for a crank slide *i'*, *k'*, or *i''*, *k''*. Each of the crank shafts *g'*, *g''* is of a total length which is less than that of the internal diameter of the cylinder *a*, so that each of the pistons *d'*, *d''* can be inserted into the cylinder *a* from one end thereof, after the crank shafts *g'*, *g''* have been placed therein. Each crank shaft is mounted in position by placing the crank shaft (*g'* or *g''*) with its crank pin *h'* or *h''* and one bearing cap *i'* or *i''* in one half of the guide *f'* or *f''*, then placing the other bearing cap *k'* or *k''* on the crank pin and finally placing the other

half of the piston d' or d^2 in position and bolting it to the first half of the piston. The bearings for the two outer crank pins of each crank-shaft consist of one-part bushings $m' m'$ or $m^2 m^2$ which are more suitable for this purpose than two-part bearings. The bushings $m' m'$ and $m^2 m^2$ are inserted through suitable cylindrical holes in the cylinder a and passed over the ends of the crank shafts g', g^2 , which have been brought into the correct position, the bushings being then secured in the cylinder a . Through one of the hollow ends of each crank shaft g', g^2 is passed a shaft o' or o^2 and connected to the crank shaft by a key p' or p^2 . On the outer ends of the shafts o', o^2 projecting into the casing b are keyed driving wheels r', r^2 . The toothed gear s for driving both wheels simultaneously is mounted between the two wheels and is mounted either directly upon the motor shaft for effecting the drive or upon a shaft driven therefrom. By reason of this arrangement and as the wheels r' and r^2 are of the same size the two crank shafts g', g^2 turn in the same time through the same angle of movement in opposite directions. The crank shafts g' and g^2 are so adjusted that they both reach the inner dead center as shown in Fig. 1, and after turning through 180° both reach the outer dead center simultaneously.

In the construction shown three cylinder spaces are formed, an inner cylinder space between the two pistons d' and d^2 , and two outer cylinder spaces one between the piston d' and the cylinder cover c' and the other between the piston d^2 and the cylinder cover c^2 . The inner cylinder space is connected by a passage to a port u , to which a line of piping may be connected. The two outer cylinder spaces communicate at their outer ends with ports $v' v^2$ which are connected by passages w' and w^2 to a port x provided at the central plane of the cylinder (Figs. 1 and 2).

The machine illustrated in Figs. 1-3 has the disadvantage that the pistons must be heavy in consequence of the straight guides f' and f^2 therein, and that even with good lubrication the crank drive consumes a considerable amount of power while with insufficient lubrication the consumption of power becomes very excessive.

According to the construction shown in Figs. 4 to 6, in which corresponding parts are indicated by the same references as in Figs. 1-3, the above-mentioned disadvantages are overcome by replacing the crank slide by a connecting rod mounted in the interior of the piston so that the weight of the piston is considerably reduced.

Each of the pistons d', d^2 is a closed-ended cylinder with comparatively thin walls, the outer end being marked 1 and the inner end being marked 2. The cylindrical wall

of each piston d', d^2 is formed in its central plane adjacent the crank shaft with two oppositely disposed wide openings 3 (through which the crank shaft passes). In a central plane perpendicular to the crank shaft two oppositely disposed narrow openings 4, 4 are formed; through one of these openings 4, the lubricating oil is introduced to the crank pin. In a central opening in the outer end 1 of each piston is mounted by means of a screwed cap 5 a bearing block 6 for the crosshead pin 7. To the pin 7 is connected the connecting rod z' or z^2 which engages with the crank pin of the crank shaft g' or g^2 . In this case as in that of Figs. 1 to 3, the piston d', d^2 can be introduced into the cylinder a from one end after the crank shafts g', g^2 and the connecting rods z' and z^2 have been placed therein.

I claim:

1. A machine for use in transmitting energy by means of alternately moving air-columns, comprising a cylinder, a piston mounted for reciprocation in said cylinder, a crank shaft arranged in the interior of said piston, said crank shaft being shorter in length than the internal diameter of the cylinder, means operatively connecting the crank-shaft to the piston, bushings in the cylinder walls supporting the crank shaft, and driving means for the crank shaft.

2. A machine for use in transmitting energy by means of alternately moving air-columns, comprising a closed-ended cylinder having two ports and means of communication between the central part of the cylinder and one of the ports and between the ends of the cylinder and the other port, a pair of pistons mounted for reciprocation in said cylinder, a crank-shaft arranged in the interior of each of the pistons, said crank-shafts being shorter in length than the internal diameter of the cylinder, stationary bushings in the cylinder walls for supporting the crank-shafts, means operatively connecting the crank-shafts to their respective pistons, and driving means for said crank-shafts, said driving means being so arranged that the pistons are moved toward and away from one another alternately at the same speed.

3. A machine for use in transmitting energy by means of alternately moving air-columns, comprising a cylinder, a pair of closed-ended hollow pistons mounted for reciprocation in said cylinder, a crank-shaft arranged in the interior of each of said pistons, each of said crank-shafts being shorter than the internal diameter of said cylinder, whereby it is rendered possible to insert the pistons in the cylinder with the crank-shafts in place in said pistons, each of said pistons being formed with slots in its side walls adjacent the ends of the crank shafts, means for driving said crank shafts at the

same speed in opposite directions, a pivot pin in one end of each piston and means for securing it therein, a connecting rod between the pivot pin and crank pin in each piston, 5 and ports communicating respectively with the center and with the ends of said cylinder.

In witness whereof I have hereunto set my hand in presence of two witnesses.

HEINRICH CHRISTIANSEN.
